UNITED STATES PATENT OFFICE.

LEWIS AUGUSTUS ASPINWALL, OF JACKSON, MICHIGAN, ASSIGNOR TO ASPINWALL MANUFACTURING CO., OF JACKSON, MICHIGAN, A CORPORATION OF MICHIGAN.

LIQUID-SPRAYER.

1,018,804.

Specification of Letters Patent. Patented Feb. 27, 1912.

Application filed June 9, 1909. Serial No. 501,097.

To all whom it may concern:

Be it known that I, LEWIS AUGUSTUS ASPINWALL, a citizen of the United States of America, residing at Jackson, in the county 5 of Jackson and State of Michigan, have invented an Improvement in Liquid-Sprayers, of which the following is a specification.

My invention relates to a device employed for spraying liquid upon growing plants or 10 vines in rows, such plants and vines as potatoes, tomatoes, strawberries, cotton and the like, and this device is adapted to be moved about from place to place for this purpose.

This invention is an improvement upon 15 the devices shown and described in Letters Patent granted to me August 7, 1906, #828,175, and August 27, 1907, #864,501.

The device of my present invention relates particularly to the pump structure and to 20 the means for actuating the same, with the object of supplying a high-pressure pump controllable and adjustable for varying pressures of say 50 to 100 lbs. according to the consistency of the liquid employed, the number 25 and size of the nozzles and the consequent distance away and size of the object to be sprayed, and the further object of maintaining the pressure uniform according to the conditions present and the results 30 sought.

In carrying out my invention and in combination with the usual devices employed heretofore by me and shown and described in said patents for supplying the pump with 35 liquid and supplying the liquid to the nozzles, and also with the air-chamber, I employ a pump that is double-ended; the pistons thereof being so connected as to act to force the liquid with an adjustable pressure 40 according as the device or features of my improvement may be predetermined and set; it being preferable to impart to one of said pistons an accelerated movement over the other.

45 The features of my improvement are actuated from the crank and crank shaft of the gear connected to the main axle and devices connected therewith and extending therefrom coupled to the opposite ends of the two 50 pistons and employed in connection with toggle-bars and adjustable spring actuated devices which may be set to an index plate according to the pressure desired, which predetermined setting will impart more or less

movement to the toggle-bars so that with a 55 greater movement the pressure is increased and with a less movement the pressure is diminished, all of which is hereinafter more particularly described.

In the drawing, Figure 1 is a side elevation and partial section of a liquid sprayer device showing generally the features of my present invention associated with the features of my former patents with which the same are to be employed. Fig. 2 is a plan 60 view of the majority of said parts, that is to say, the wheels of the sprayer and the liquid barrel and the particular spraying devices are omitted, and Fig. 3 is a side elevation and vertical section at the dotted line α , α , 65 Fig. 2 in larger size.

The features which are substantially common to the structure of my present invention and my former patents as herein cited, comprise a main axle 2, vehicle wheels 3, a large 70 gear 4, on the main axle and a small gear 5 on an auxiliary or crank shaft g .

67 8 and 9 represent frame members carried by the main axle 2 and upon which are supported the liquid spraying mechanism. 80

10 represents the draft members by which the vehicle is pulled, and 14, 15 are supports therefor from the frame members.

11 are the spraying devices, and 12 and 13 are adjustable supports for the spraying devices said members 12 and 13 being supported by the aforesaid members 14 and 15. 85

16 represents the liquid holding barrel and 17 the swinging paddle within the same, and 18 a pipe for delivering the liquid from the 90 barrel to the pump or air-chamber 19.

The special features of my present invention comprise the pump cylinders a a^1 and an intermediate chamber a^2 into which the liquid is drawn and from which it is forced 95 into the air-chamber to be delivered to the spraying devices. The particular structure through which the liquid passes however, forms no part of my present invention. This pump structure is preferably of the 100 form described and shown in an application for Letters Patent of the United States, filed by me on June 3, 1909, Serial #499,968, namely, with a double cylinder, or in other words, two aligned open-ended cylinders and 105 two pistons and their piston-rod. The pump cylinders are supported upon a platform or girder b being bolted thereto at the

feet 20 of the pump cylinder and at the end of this platform or girder *b* I provide brackets *b*¹ *b*² in which the respective ends *c* *c*¹ of the pistons of the pump cylinder slide 5 and are guided.

d *d*¹ are bars secured by bolts to the piston ends *c* *c*¹ and these bars at similar ends are connected by rocker arms 21 to bracket members secured to the frame member 8. 10 The bar *d* is at its opposite end connected by a pivot 22 to a bracket *e*¹ and frame *e*. The bar *d*¹ is connected at its complementary end by a rocker arm 21 to a bracket *e*². Therefore when the bar *e* and its brackets *e*¹ *e*² are given a back and forth movement the piston ends *c* *c*¹ and pistons are reciprocated with the movement, the extent of which is governed and controlled by the relation of the bars *d* *d*¹, the rocker arms 21 15 and the frame *e* and its brackets *e*¹ *e*². The rocker arms 21, in their operative relation to the other parts, produce a lost motion effect which permits the piston end *c*¹ to lag behind and shorten its stroke relative to the 20 stroke of the piston end *c*. The lost motion effect of the rocker arms 21 is varied by the adjustment of the toggle bars *k* *k*¹. More or less movement may be imparted to the members just described and consequently 25 more or less pressure through the air-chamber may be created in proportion to the length of the stroke of the pump and consequent amount of liquid passed into the air-chamber.

30 I employ a casting which includes an arm *f* connected by a pivot 23 with the bracket *e*¹, an index plate *f*¹ and side bars *f*². The index plate *f*¹ is a rising portion of the frame; it is provided as shown in Fig. 3, 35 with a toothed edge of five teeth, from each one of which extends a line and indicating numerals or letters; for instance the letters S. N. meaning small nozzles and L. N. large nozzles. The numerals to the left of these 40 letters indicate the number of nozzles and the numerals to the right the pressure. Consequently in reading this index plate, one reads 4 small nozzles 50 lbs.; 4 large 45 nozzles 80 lbs.; 8 small nozzles 50 lbs. and 8 large nozzles 80 lbs.

50 *g* as hereinbefore indicated is the auxiliary or crank shaft and upon the same is a crank *g*¹ with a usual crank pin.

h represents a yoke and *h*¹ its complementary yoke head connected to the crank pin of the crank *g*¹. This yoke head is provided with a side recess receiving a slide bar *i* and to which the same is connected by bolts shown in Fig. 3. The yoke head is also provided with a segment guide *h*². This slide bar *i* is received in a suitable groove-way in the side-bars *f*² of the casting which forms the arm *f*, index plate *f*¹ and side bars *f*², and on the opposite end of the slide bar *i* is a shoulder *i*¹ adapted in the extreme movement to

come closely adjacent to one end of the side bars *f*² in said casting and prevent the slide bar *i* coming out of the groove-way.

k *k*¹ are toggle bars pivotally connected together and at their respective ends the bar *k* is provided to the arm *f* and the bar *k*¹ pivoted to the yoke head *h*¹. A rocker-arm *l* is pivoted to a vertical bar *m* as shown in Fig. 3, and said rocker-arm at one end carries a roller *l*¹ adapted to bear upon the upper surface of the toggle-bar *k* and a spring *n* is connected at its lower end to the end of the rocker-arm *l* opposite to the end to which the roller *l*¹ is connected. The bar *m* is made with an A-shaped head *m*¹ and in the top of this head there is an opening to receive a bolt *n*¹ having an adjustable clamping nut and to which the upper end of the spring *n* is connected. The lower free end of this A-head *m*¹ comes adjacent to the index plate *f*¹ and is intended by its adjustable position and relation to the teeth of the index plate, to indicate the number and size of the nozzles and pressure; the same being predeterminedly set according to the result 90 to be obtained.

The lower end of the vertical bar *m* is provided with holes 24 in series; the holes in each series agreeing in number with the number of teeth or projections on the index plate *f*¹, and I employ bolts 25 which secure the vertical bar *m* in a predeterminedly adjustable relation to the side bar *f*² of said casting. This adjustment is very easily and quickly effected so as to change the relation of the bar *m* to the side bar *f*² so as to raise or lower the same and in so doing adjust the position of the free end of the A-shaped head *m*¹ to the marks on the index plate, for it must be apparent that the lower down the vertical bar *m* is placed in its relation to the side-bar *f*², the lower will be the free end of the A-head *m*¹ in its relation to the index plate *f*¹ to indicate the pressure, and consequently the greater will be the tension applied by the spring *n* to the rocker-arm *l* and its roller *l*¹ against the toggle-bars. This pressure means an increased movement to the pump pistons and an increased flow of liquid and consequently greater pressure 115 upon the vertical bar *m* with relation to the side-bars *f*² and a higher mark of the index-plate means a release of the tension of the spring *n* and consequently increased movement to the toggle-bars and consequently decreased movement to the pump pistons and a less flow of liquid and less pressure.

In the operation of the device, the revolution of the main axle 2 by the vehicle wheels as the liquid sprayer is drawn over the ground turns the gear 4 and therefrom the gear 5, the crank-shaft *g* and the crank *g*¹ and the rotary motion imparted thus to the crank and its crank pin swings all the parts connected to the crank pin upon the 125

pivot pin 23 of the casting to the bracket e^1 , imparting therefore to the casting, or in other words, to the arm f , index plate f^1 and side bars f^2 , the yoke h , the yoke-head h^1 , 5 segment h^2 , the toggle-bars k k^1 , the vertical bar m , its A-shaped head m^1 , the rocker-arm l and its roller l^1 an up and down swinging motion and to the slide bar i , side bars f^2 , the yoke h , yoke-head h^1 , segment h^2 and 10 toggle-bars k k^1 also a reciprocating motion, simultaneously, and the straightening action of the toggle-bars k k^1 through the power of the spring n exerted upon the rocker-arm l and roller l^1 effects through the 15 parts hereinbefore described by their connection through the arm f and pivot 23 with the bars d d^1 , frame e , brackets e^1 e^2 and link 21 a reciprocating action of the pump pistons by the connection of said parts to the 20 piston ends c c^1 effecting the drawing of the spraying liquid from the barrel 16 through the pump cylinders, the air-chamber and to the spraying devices, and in this motion the stroke for both pumps may be alike or the 25 stroke may be varied. The adjustment of the parts by changing the position of the part m varies and determines the tension of the spring n and this determines and results in a variation of the throw or stroke of the 30 pistons so that the pump piston nearest to the main axle may receive less pressure and movement than the one at the rear. The motion imparted to the piston is through the crank g^1 and connection h , to which is attached the sliding bar i with stop shoulder i^1 at the opposite end, as seen in Figs. 1 and 3. The sliding bar is inclosed in the casting f by plate f^2 Fig. 2. The casting h^1 forming the connection with the crank is 35 connected with casting f by means of toggle-bars k and k^1 , which through the sliding motion of the bar i , causes them to toggle toward the roller l^1 on the bar l attached to the frame m . The pressure against the toggle bars is maintained through the spring n , 40 regulated by the thumb-nut n^1 . When the pressure is applied in a direction to straighten the bars, the sliding bar i moves in a direction against the stop i^1 , when the 45 liquid by suction is drawn into cylinder a , at which time the liquid in cylinder a^1 is being forced out (requiring the greatest pressure) the bar i being kept from sliding by said stop i^1 . On the reverse motion the 50 liquid in cylinder a receives the pressure and the cylinder a^1 the suction, which yields to the sliding of the bar i causing the toggle bars to move upward against the roller l^1 , receiving a pressure as required through adjustment of the nut n^1 . A further adjustment is obtained through setting the frame m up or down by means of the series of holes 55 24 and bolts 25, which are also in the casting f . By this adjustment the various points on 60 the index plate are reached, thus affording

latitude of movement by the toggle to meet the desired pressure according to the size and number of nozzles used. The whole connection with frame m as shown is movable with the crank and connected by wrist pin 70 23 to the connections moving the pistons of both pumps, as shown in the specifications.

Suitable valves are of course employed in this device in connection with the pump so as to control the direction of the liquid supply and in this connection I have shown a pipe o (see Fig. 2) by which the liquid instead of being forced through the spraying devices may be returned to the pumps when it is necessary to turn the liquid spraying 80 apparatus around the end of one row in a field to start in another row, as this is preferable to disconnecting parts of the gear where the spraying function is not required.

I claim as my invention:

1. In a liquid spraying device, the combination with devices for supplying the power, of an air chamber and pump cylinders and pistons, series of devices connecting the pump pistons capable of variable 90 extent of movement, devices connecting the said series of devices with the power, and manually actuated means adapted for a predetermined adjustable relation to the series of devices connecting the pump pistons 95 so as to control the pressure in the air chamber employed to force the liquid through the sprayers.

2. In a liquid spraying device, the combination with a crank-shaft, and crank, of an air-chamber, a pump having two oppositely disposed cylinders and pistons, devices connected to and connecting the pistons and for simultaneously operating the same, a cast frame pivotally connected to 100 said devices, a member having a slidable relation in connection therewith and secured to the crank-pin of the said crank for a reciprocating and swinging movement, and means connected to the said frame and member and having an adjustable relation, whereby the pressure upon the liquid to be forced to the sprayers may be controlled as desired.

3. In a liquid spraying device, the combination with a crank shaft and crank, of an air-chamber, a pump having two oppositely disposed cylinders and pistons, devices connected to and connecting the pistons for simultaneously operating the same, a cast 115 frame pivotally connected to said devices, a member having a slidable relation in connection therewith and secured to the crank-pin of the said crank for a reciprocating and swinging movement, an index device formed as a part of said frame, a vertically movable member connected in an adjustable relation to said frame and as set simultaneously indicating a position in regard to said index device and means connected to said 120 125 130

frame, the slideable member and the vertically movable member adapted for tension in regard to the adjusted and set position of the vertically movable member so as to 5 automatically control the stroke of the pistons and the consequent pressure upon the liquid to be forced to the sprayers.

4. In a liquid spraying device, the combination with a crank shaft and crank, of 10 an air-chamber, a pump having two oppositely disposed cylinders and pistons, devices connected to and connecting the pistons for simultaneously operating the same, a casting comprising an arm pivotally mounted to said devices, an index plate and side bars; a member consisting of a yoke and yoke head connected to the crank-arm, a slide bar secured thereto and received in slide-ways in 15 said casting and adapted with a turning of the crank to move through said slide-ways with a reciprocating action and to swing the said casting on its pivot with the aforesaid devices, toggle-bars connected at their respective ends to the arm of said casting and to the yoke-head, a vertically movable member connected in an adjustable relation to 20 said casting and having an end adapted to occupy a predetermined position with refer-

ence to the index plate and means connected to said vertically movable and adjustable member acting upon the toggle-bars for applying irregular pressure thereto to straighten the same in proportion to the position occupied by said vertically adjustable member.

5. In a liquid spraying device, the combination with means for applying power and motion, of an air chamber a pump having oppositely disposed cylinders and pistons, bars connected to the ends of the pistons outside the cylinders in a parallel relation, links connecting the ends of said bars to members of the frame at one end, a frame connected in a pivotal relation with one of said bars, and a rocker-arm connecting the opposite end of said frame with the other of said bars and means connected with said frame and interposed between the same and the power devices for imparting movement thereto.

Signed by me this 3d day of June, 1909.

LEWIS AUGUSTUS ASPINWALL.
